(57) **CLAIM**

The ornamental design for a bottle stopper, as shown and described.

DESCRIPTION

FIG. 1 is a perspective view taken from the top, front, and right side of the bottle stopper of the present invention.

FIG. 2 is a left side elevational view of the bottle stopper of FIG. 1, the opposite side being nearly a mirror image thereof. FIG. 3 is a front elevational view of the bottle stopper of FIG. 1, the opposite side, rear, being a mirror image thereof.

FIG. 4 is a top plan view of the bottle stopper of FIG. 1; and, FIG. 5 is a bottom plan view of the bottle stopper of FIG. 1. The broken lines in the drawings represent unclaimed environmental subject matter and form no part of the claim.
